H. S. YOUNG

RAILWAY TRAFFIC CONTROLLING APPARATUS

Filed Feb. 20, 1924

UNITED STATES PATENT OFFICE.

HENRY S. YOUNG, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed February 20, 1924. Serial No. 394,038.

To all whom it may concern:

Be it known that I, HENRY S. YOUNG, a citizen of the United States, residing at Wilkinsburg, in the county of Allegheny and State of Pennsylvania, have invented certain new and useful Improvements in Railway-Traffic-Controlling Apparatus; of which the following is a specification.

My invention relates to railway traffic controlling apparatus, and particularly to signaling apparatus for stretches of single track over which traffic moves in both directions.

I will describe one form of railway traffic controlling apparatus embodying my invention, and will then point out the novel features thereof in claims.

The accompanying drawing is a diagrammatic view showing one form and arrangement of apparatus embodying my invention.

Referring to this drawing the reference characters 1 and 1^a designate the track rails of a railway over which traffic moves in both directions. The stretch of track shown in the drawing is separated from the rest of the track by passing sidings O and M located at the left hand and right hand ends of this stretch, respectively. It is understood that any number of such stretches of single track and associated passing siding may be placed end to end to form a complete system. The rails 1 and 1^a of the stretch of track here shown are divided by means of insulated joints 2 into a plurality of successive track sections A—B, B—C, C—D, D—E, E—F, F—G, respectively. Each track section is provided with a track relay designated by the reference character R with an appropriate exponent connected across the rails adjacent one end of the section. A suitable source of energy such as a track battery 7 is connected across the other end of each section. A resistor 8 is interposed between each track battery 7 and one rail of the associated section in the usual manner.

The stretch of track is also provided with two pole changing relays P' P² located adjacent points A and G, respectively. The control of these relays is well understood and forms no part of the present disclosure, so it is omitted from the drawing for the sake of simplicity. It is sufficient to state that relay P' is so controlled that under normal conditions this relay is energized,

but that it is de-energized from the time an eastbound train passes the first passing siding to the left of siding O until the train passes point A, and is also de-energized from the time a westbound train passes point A until such train reaches a point in the first section to the left of siding O. For an illustration of one means for controlling this relay in the manner specified in United States Patent No. 1,322,317 granted to R. A. McCann on Nov. 18, 1919, wherein the pole changing relay is designated P. The control of relay P² is similar to that just described for relay P'.

Associated with each track relay is a line relay designated by the reference character H with a distinguishing exponent. Each of the line relays is provided with a slow-acting repeater relay designated by the reference character K with an exponent corresponding to the location, except that as here shown such repeater relays are not provided for line relays H' and H². Relays H³ and H⁴ are each further provided with a stick relay designated by the reference character J with a suitable exponent.

Each of the line relays is responsive to reversal of the relative polarity of the current supplied thereto. The circuit for relay H' passes from a suitable source of energy such as a battery Q³, over wires 27, 28, 77, 78 and 79, front contact 80 of relay H³, wire 113, normal contact 114 of relay H³, wires 115 and 33, front contact 34 of slow-acting relay K³, wire 35, front contact 36 of track relay R⁶, wire 37, front contact 38 of track relay R', wire 39, winding of relay H', wires 40, 20 and 41, front contact 42 of relay K³, and wires 43, 44, 45 and 46 back to battery Q³. This circuit is closed when relays K³, R' and R⁶ are energized and relay H³ is energized in the normal direction. Under which conditions relay H' is energized in the normal direction and contact 87 thereon is swung to the left. If relay K³ is de-energized and relay J³ energized the circuit for relay H' may be traced from battery Q³, through wires 46, 45, 44 and 43, back contact 34 of relay K³, thence as before through relay H' to back contact 42 of relay K³, wires 48 and 31, contact 30 of relay J³, and wires 29, 28 and 27 to battery Q³. When this circuit is closed relay H' is energized in the reverse direction and

- contact 87 is swung to the right. It is therefore plain that when relay J^3 is energized, relay H^3 is removed from the control of relay H' . It is also plain from the foregoing that relay H' is energized in one direction or the other according as relay K^3 is energized or de-energized. Relay H^2 is controlled over circuits similar to those just traced for relay H' .
- 10 Line relay H^6 is provided with a circuit which passes from battery Q' , through wires 9 and 10, front contact 11 of relay P' , wire 12, front contact 13 of relay R' , wire 14, back contact 15 of relay J^3 , wire 16, front contact 17 of relay R^6 , wire 18, winding of relay H^6 , wires 19, 20 and 21, front contact 22 of relay P' , and wires 23, 24 and 25 back to battery Q' . When relay P' is de-energized current flows from battery Q' , through wires 25, 24 and 23, back contact 11 of relay P' , thence as before through relay H^6 to back contact 22 of relay P' , and wires 26 and 9 back to battery Q' . It follows that when relays R' and R^6 are energized and relay J^3 is de-energized, relay H^6 is energized in the normal or reverse direction according as relay P' is energized or de-energized. The control of relay H^6 is similar to the control of relay H^3 .
- 30 One circuit for relay H^3 may be traced from battery Q^5 through wires 49, 50 and 51, front contact 52 of relay K^5 , wire 53, back contact 54 of relay J^4 , wire 55, front contact 56 of relay R^4 , wire 57, front contact 58 of relay R^3 , wire 59, winding of relay H^3 , wires 60, 61 and 62, front contact 63 of relay K^5 , and wires 64, 65 and 66 back to battery Q^5 . When relay K^5 is de-energized current flows from battery Q^5 , through wires 66, 65 and 64, back contact 52 of relay K^5 , and thence as before through relay H^3 to back contact 63 of relay K^5 and wires 67, 50 and 49 back to battery Q^5 . It will therefore be clear that when relays R^3 and R^4 are energized, and relay J^4 is de-energized, relay H^3 is energized in the normal or reverse direction according as relay K^5 is energized or de-energized. Relay H^4 is controlled by relay K^6 as just described for the control of relay H^3 by relay K^5 .

50 Each slow-acting repeater relay K is arranged to be energized when the associated line relay H is energized. Referring particularly to relay K^6 , a circuit is provided over which current flows from battery Q^6 , through wire 168, front contact 169 of relay H^6 , wire 170, winding of relay K^6 , and wires 171, 172 and 173, back to battery Q^6 . When relay H^6 becomes de-energized, this circuit is of course, opened but due to the slow acting characteristics of relay K^6 a considerable interval of time elapses before this relay opens its front contacts. This time interval is increased by short circuit-

ing the relay over a snubbing path which passes from one side of relay K^6 , through wire 170, back contact 169 of relay H^6 , and wires 174, 175 and 171 back to relay K^6 .

Stick relay J^3 is provided with a pick-up circuit which may be traced from battery Q^3 , through wires 27 and 68, back contact 69 of relay R^6 , wire 70, back contact 71 of relay R^3 , wire 72, front contact 73 of relay K^3 , wires 74 and 75, winding of relay J^3 , and wires 76 and 46 back to battery Q^3 . Relay J^3 can be energized, then, only when an eastbound train enters section C—D, because when a westbound train passes through the stretch contact 73 opens before contacts 69 and 71 close. The relay J^3 is also provided with a stick circuit over which current flows from battery Q^3 , through wires 27, 28, 77, 78 and 79, back contact 80 of relay H^3 , wires 81 and 82, front contact 83 of relay J^3 , wires 84 and 75, winding of relay J^3 , and wires 76 and 46 back to battery Q^3 . This stick circuit is provided with a branch which passes from wire 79, through front contact 80 of relay H^3 , wire 113, reverse contact 114 of relay H^3 , and wire 116 to wire 82. It will therefore be clear that after stick relay J^3 has been energized by the entrance of an eastbound train into section C—D, the relay will subsequently be maintained in its energized condition over back contact 80 of relay H^3 as long as such train is between points C and E, and will be energized when such train is in section E—F, over reverse contact 114 of relay H^3 .

The control of relay J^4 is similar to that just explained for relay J^3 .

Eastbound traffic over the stretch of track shown in the drawing is governed by track-way signals S' , S^3 and S^5 located at points A, C and E, respectively, and westbound traffic is governed by signals S^2 , S^4 and S^6 located at points G, E and C, respectively. These signals may be of any suitable form, and are here shown as light signals each comprising three light units 4, 5 and 6 arranged when energized to display a "stop," a "caution," or a "proceed" indication, respectively. Referring particularly to signal S' , when relay H' is energized in the normal direction current flows from battery Q' , through wire 9, front contact 85 of relay H' , wire 86, normal contact 87 of relay H' , wire 88, proceed unit 6 of signal S' , and wire 89 back to battery Q' . When this circuit is closed the signal S' displays a proceed indication. When relay H' is energized in the reverse direction current flows from battery Q' , through wire 9, front contact 85 of relay H' , wire 86, reverse contact 87 of relay H' , wire 90, caution unit 5 of signal S' , and wires 89 and 25 back to battery Q' , and the signal then displays a "caution" indication. If relay H' is de-en-

ergized, stop unit 4 of signal S' is energized by a circuit which passes from battery Q', through wire 9, back contact 85 of relay H', wire 91, stop units 4 of signal S', and wires 5 89 and 25 back to battery Q' and the signal then displays a "stop" indication. The control of signal S² by relay H² is similar to the control of signal S' by relay P'.

The proceed circuit for signal S⁶ passes 10 from battery Q⁶ through wires 168 and 92, front contact 93 of relay K⁶, wire 94, normal contact 95 of relay H⁶, wire 96, proceed unit 6 of signal S⁶, and wires 97, 175, 172 and 173 back to battery Q⁶. The caution 15 circuit for this signal may be traced from battery Q⁶, through wires 168 and 92, front contact 93 of relay K⁶, wire 94, reverse contact 95 of relay H⁶, wire 98, caution unit 5 of signal S⁶, and wires 97, 175, 172 20 and 173, back to battery Q⁶. When relay K⁶ is de-energized current flows from battery Q⁶, through wires 168 and 92, back contact 93 of relay K⁶, wire 99, stop unit 4 of signal S⁶, and wires 97, 175, 172 and 25 173, back to battery Q⁶ and signal S⁶ displays a stop indication. The circuits for signal S⁶ are similar to those just traced for signal S².

The proceed circuit for signal S³ is 30 closed when relay K³ is energized and relay H³ is energized in the normal direction, under which conditions current flows from battery Q³, through wires 27, 28, 77 and 101, front contact 102 of relay K³, wire 103, normal contact 104 of relay H³, wire 105, proceed unit 6 of signal S³, and wires 106, 45 and 46 back to battery Q³. A caution 35 circuit for signal S³ passes from battery Q³, through wires 27, 28, 77 and 101, front contact 102 of relay K³, wire 103, reverse contact 104 of relay H³, wire 107, front contact 108 of relay J³, wire 109, caution unit 5 of signal S³ and wires 106, 45 and 46 back to battery Q³. This circuit is closed when 40 relays K³ and J³ are both energized and relay H³ is energized in the reverse direction. Signal S³ then displays a caution indication. One circuit for the stop unit 4 may be traced from battery Q³, through wires 27, 28, 77 and 101, back contact 102 of relay K³, wires 45 112 and 111, stop unit 4 of signal S³, and wires 106, 45 and 46 back to battery Q³. The circuit just traced is provided with a branch over which current flows from wire 50 101, through front contact 102 of relay K³, reverse contact 104 of relay H³, wire 107, back contact 108 of relay J³, and wire 110 back to wire 111. It will therefore be clear 55 that signal S³ displays a stop indication when relay K³ is de-energized, and also when relay K³ is energized, relay H³ is energized in the reverse direction and relay J³ is de-energized.

Signal S⁴ is provided with circuits similar 60 to those associated with signal S³.

As shown in the drawing all parts of the apparatus are in the position corresponding to the unoccupied condition of the track. Under these circumstances all track relays are energized, all line relays H are energized 70 in the normal direction, all slow-acting relays K are energized, both stick relays J³ and J⁴ are de-energized, and pole changing relays P' and P² are energized. Each of the signals S therefore displays a proceed indication. It will now explain the operation of the apparatus as an eastbound train proceeds along the track.

Prior to the entrance of this train into the stretch shown in the drawing, relay P' becomes de-energized, thus causing relay H² to be energized in the reverse direction and causing signal S⁶ to indicate caution.

As the train enters section A—B, relay R' is de-energized. The circuit for relay H² is then broken at front contact 38 of relay R' and relay H' thereupon becomes de-energized. At the same time, relay H⁶ is de-energized by the opening of front contact 13 of relay R'. The closing of back contact 85 of line relay H' closes the circuit for stop unit 4 of signal S', which signal now displays a stop indication. The opening of front contact 169 of relay H⁶ causes relay K⁶ to become de-energized, and after a time 95 interval back contact 93 of relay K⁶ closes to cause signal S⁶ to indicate stop. The de-energization of relay K⁶ also reverses the polarity of the current supplied to relay H⁶, which latter relay is now energized in the 100 reverse direction. The circuit is therefore, closed for stop unit 4 of signal S⁴ over reverse contact 117 of relay H⁴ and back contact 118 of relay J⁴. Signal S⁴ therefore displays a stop indication. The opening of 105 normal contact 119 of relay H⁴ opens one branch of the circuit for relay H² and the other branch for this circuit is already open at front contact 120 of relay J⁴ so relay H² becomes de-energized and causes signal S² 110 to indicate stop. It is therefore clear that a train entering the stretch of single track between two passing sidings will set all opposing signals in such stretch at stop. When the train enters section B—C, relay R² becomes de-energized but the remaining apparatus is not affected. When the train moves into section C—D, relay R² becomes de-energized. The circuit for relay H⁴ is then 115 broken at front contact 160, and relay H⁴ therefore opens. Signal S⁴ therefore continues to indicate stop, the stop circuit now passing over back contact 126 of relay K⁴, now de-energized. The opening of front contact 58 of relay R² causes relay H² to 120 become de-energized. Relay K³ therefore becomes de-energized. During the time interval after the closing of the back contacts of relay R² and prior to the opening of the front contacts on relay K³, the pick-

125 130

up circuit for stick relay J^3 is closed. The stick relay is subsequently maintained in its energized condition over a stick circuit including back contact 80 of relay H^3 . The de-energization of relay K^3 also causes signal S^3 to indicate stop. As the train moves out of section A—B relay R' picks up. Relay P' also picks up but this does not affect the apparatus since the circuit for relay H^6 is opened at front contact 17 of relay R' and also at back contact 15 of relay J^3 . As the train moves out of section B—C relay R' picks up, thus completing the circuit for relay H' through back contacts of K^3 and front contacts of J^3 , so that relay H' therefore becomes energized in the reverse direction, and signal S' indicates caution. As the train moves into section D—E, relay R^4 becomes de-energized which holds open the circuit for relays H^3 and H^4 . Signals S^3 and S^4 therefore continue to indicate stop. When the train enters section E—F, the shunting of relay R^5 causes the de-energization of relays H^5 and K^5 and signal S^5 therefore indicates stop. The pick up circuit for relay J^4 is open at front contact 130 of relay K^4 and relay J^4 therefore remains in its de-energized condition. As the train successively clears sections C—D and D—E, relays R^3 and R^4 pick up, closing the circuit for relay H^3 . Relay K^5 is de-energized however and relay H^3 is therefore energized in the reverse direction. Signal S^3 then displays a caution indication. The closing of relay K^3 energizes relay H' in the normal direction and signal S' now indicates proceed. It should, however be pointed out that relay J^3 is still energized over a stick circuit including reverse contact 114 of relay H^3 and signal S^6 still indicates stop, because the current for relay H^6 is broken at back contact 15 of relay J^3 . Relay R^2 becomes de-energized as the train enters section F—G but this does not affect the remaining apparatus. When the train enters the section to the right of point G relay P^2 becomes de-energized. When the train successively clears sections E—F and F—G, the closing of relays R^2 and R^5 completes the current for relay H^5 , which latter relay becomes energized in the reverse direction, picking up relay K^5 and causing signal S^5 to indicate caution. The closing of relay K^5 energizes relay H^3 in the normal direction, thus causing signal S^3 to indicate proceed. At the same time relay J^3 is de-energized, thus closing the circuit for relay H^6 and allowing signal S^6 to indicate proceed. The opening of relay J^3 and the closing of relay K^6 supplies current of normal relative polarity to relay H^4 and this relay becomes energized, thus picking up relay K^4 . Signal S^4 then displays a proceed indication. When the train clears section F—G, the energization of relay R^2 also energizes relay H^2 , thereby causing signal

S^2 to display a proceed indication. When relay P^2 becomes energized, as the train reaches a point in the section to the right of siding M, relay H^5 is energized in the normal direction, and signal S^5 displays a proceed indication thus returning the apparatus to the normal condition. 79

The operation of the apparatus as a west-bound train passes through the stretch of track will be readily understood from the foregoing. 75

Although I have herein shown and described only one form of railway traffic controlling apparatus embodying my invention, it is understood that various changes and modifications may be made therein within the scope of the appended claims without departing from the spirit and scope of my invention. 89

Having thus described my invention, what I claim is: 85

1. Railway traffic controlling apparatus comprising a stretch of railway track, a line relay comprising a normal contact and a reverse contact, means for controlling said relay in accordance with traffic conditions, a slow acting relay arranged to be energized whenever said line relay is energized, a stick relay controlled by said line relay and said slow acting relay, a trackway signal, means including a front contact on said stick relay and said reverse contact for causing said signal to display a caution indication, and means for causing said signal to display a proceed indication when said slow acting relay is energized and said normal contact is closed. 95

2. Railway traffic controlling apparatus comprising a stretch of railway track, a line relay comprising a normal contact and a reverse contact, means for controlling said relay in accordance with traffic conditions, a slow acting relay arranged to be energized whenever said line relay is energized, a stick relay controlled by said line relay and said slow acting relay, a trackway signal, a circuit for causing said signal to display a stop indication and including a back contact of said slow acting relay, and a branch for said circuit including the reverse contact of said line relay and a back contact of said stick relay. 105 110 115

3. Railway traffic controlling apparatus comprising a stretch of railway track, a line relay comprising a normal contact and a reverse contact, means for controlling said relay in accordance with traffic conditions, a slow acting relay arranged to be energized whenever said line relay is energized, a stick relay controlled by said line relay and said slow acting relay, a second line relay, a circuit for said second line relay controlled by said slow acting relay and by said stick relay, means including the normal contact of said first line relay for at times removing 120 125 130

said stick relay from the control of said second line relay and traffic governing means controlled by said first line relay.

4. In combination, a stretch of railway track, a signal for governing traffic in one direction over said stretch, a line relay associated with said signal, means effective when a train moves through said stretch in the direction in which said signal governs traffic for de-energizing the relay when the train passes the signal, for energizing said relay in the reverse direction when the train reaches a point in advance of the signal and for energizing the relay in the normal direction when the train reaches a second point in advance of the signal; means effective when a train moves through the stretch in the opposite direction for energizing the relay in the reverse direction when the train passes a point in advance of the signal, for de-energizing the relay when the train reaches a second point between the last mentioned point and the signal, and for energizing the relay in the normal direction after the train passes the signal, a slow acting relay arranged to be energized when said line relay is energized in either direction, a stick relay arranged to be energized when a train passes said signal in the direction in which the signal governs and to be subsequently maintained in its energized condition till the train passes said second point in advance of the signal, a proceed circuit for said signal closed only when said line relay is energized in the normal direction; a caution circuit for said signal closed when said line relay is energized in the reverse direction, said slow acting relay is energized, and said stick relay is energized, a stop circuit for said signal closed when said slow acting relay is de-energized; and an auxiliary stop circuit for said signal closed when said line relay is energized in the reverse direction, said slow acting relay is energized, and said stick relay is de-energized.
5. In combination, a stretch of railway track, a forward signal and a rear signal for governing traffic in one direction over said stretch, a first line relay associated with said forward signal, a second line relay associated with said rear signal, means effective when a train moves through said stretch in the direction in which said signals govern to de-energize said first relay when the train passes the forward signal and to energize said first relay in the reverse direction when the train reaches a point in advance of the forward signal but to energize such first relay in the normal direction when the train reaches a second point in advance of the
- forward signal, means effective when the train moves through the stretch in the opposite direction for energizing the first relay in the reverse direction when the train passes a point in advance of the forward signal and for de-energizing the first relay when the train reaches a second point between the last mentioned point and the forward signal and for energizing the first relay in the normal direction when the train passes the rear signal, a slow acting relay arranged to be energized when said first line relay is energized in either direction, a stick relay arranged to be energized when a train passes said forward signal and to be subsequently maintained in its energized condition till the train passes said second point in advance of the signal, a proceed circuit for said forward signal including a front contact of said slow acting relay and a normal contact of said first line relay; a caution circuit for said forward signal including a front contact of said slow acting relay, a reverse contact of said first line relay, and a front contact of said stick relay; a stop circuit for the forward signal including a back contact of said slow acting relay; a second stop circuit for said forward signal including a front contact of said slow acting relay, a reverse contact of said first line relay and a back contact of said stick relay; means for energizing said second line relay in the reverse direction when said first line relay and said slow acting relay are de-energized but said stick relay is energized, means for energizing said second line relay in the normal direction when said first line relay is energized in the reverse direction and said slow acting relay and said stick relay are energized, means for also energizing said second line relay in the normal direction when said first line relay is energized in the normal direction, said slow acting relay is energized and said stick relay is de-energized; means for de-energizing said second relay when a train is between said signals or from the time a train approaching said signal in a direction opposite to that in which the signal governs passes said second point in advance of the signals till such train passes the rear signal; and means for controlling said rear signal so as to indicate proceed when said second line relay is energized in the normal direction, to indicate caution when such second line relay is energized in the reverse direction, and to indicate stop when the second line relay is de-energized.

In testimony whereof I affix my signature.

HENRY S. YOUNG.
